UNITED STATES PATENT OFFICE.

FRANK W. MOORE, OF WAUPUN, WISCONSIN.

EAR-RING.

SPECIFICATION forming part of Letters Patent No. 293,268, dated February 12, 1884.

Application filed June 6, 1883. (No model.)

To all whom it may concern:

Be it known that I, FRANK W. MOORE, a citizen of the United States, residing at Waupun, in the county of Dodge and State of Wisconsin, have invented a new and useful Ear-Ring, of which the following is a specification.

My invention relates to improvements in the ring proper, or clasp-attacher, to the drop or pendant-plate in ear-rings; and the objects 10 of my improvements are, first, to do away with the use of solder, with its attendant expense and heat; second, to preserve the temper and durability of the wires or bars forming the ring; and, third, to provide a spring- 15 hinge, attached to its seat, at a nominal expense of construction. I attain these objects by the mechanism illustrated in the accompanying drawing, which is a perspective view of the entire device.

With punch and die I cut and raise on the plate x the strap A . At one end of the wire or bar y , I bend the loop B , and then pass the wire under the strap A , leaving the loop well out of the strap. I then pass one end of the 25 wire or bar z under, from the back of, the loop B , and twist it through and about the loop, thus forming the hinge-joint $B C$, with the double wire resting on the plate x . The end of the wire is clipped and bent to form 30 the tongue c . I now draw the wire y forward through the strap until the loop and twist forming the hinge-joint $B C$ are brought snugly against the edge of the strap A , in which po-

sition it is secured firmly, by means of the sharp bend b , against the opposite edge of the 35 strap. The wires or bars $y z$ are then formed into the desired shape and proportions to complete the ring and clasp. The tongue c is adapted, in connection with the flexible wire z , for its use as a spring-stop to stiffen the 40 clasp of the respective ends of the wires $y z$.

Having thus shown the nature and construction of my device, I claim as my invention—

1. In an ear-ring, the strap A , raised from the plate x , in combination with the bar y , for 45 the purposes set forth.

2. The combination of the loop B and coil C , the bar y , bent at b , and strap A , raised from the plate x , as and for the purpose de- 50 scribed.

3. In a spring-clasp for ear-rings, the combination of the bar z , having a coil, C , and tongue c , with the bar y through the strap A of the plate x , and the loop B , as and for the 55 purpose set forth.

4. The combination, in a hinged and spring-clasped ear-ring, of the strap A on plate x , the bar y , having bend b , and loop B , secured to the plate by means of the strap, the flexible bar z , having coil C and tongue c , the loop 60 and coil being united to form a hinge, substantially as set forth.

FRANK W. MOORE.
